AUTOMATIC PRESSURE CONTROL FOR
LOW-TEMPERATURE, LOW-PRESSURE
FRACTIONATING COLUMNSDonald R. Douslin, Bartlesville, Okla., assignor to
Phillips Petroleum Company, a corporation of
Delaware

Application December 7, 1942, Serial No. 468,148

2 Claims. (Cl. 202—160)

This invention relates to an automatic pressure controlled analytical fractionating apparatus and is particularly applicable, although not necessarily restricted, to the analysis of hydrocarbon gases and liquids or mixtures of hydrocarbon gases and liquids such as natural gas, natural gasoline, gasoline and other petroleum distillates or in fact any mixture of materials which is capable of analysis by distillation under conditions of low temperatures and pressures and especially where the pressure within the fractionating column must be very carefully controlled.

It is the purpose of this invention to provide a valve or similar device which is automatically operable directly in response to pressure fluctuation within the column to influence the air flow from a constant pressure source in such a manner as to force quantities of cooling agent to the condensing section and thereby regulate accurately the fractionation pressure. In some respects, the present invention is an improvement on the patent to W. J. Podbielnak No. 1,967,258, issued July 24, 1934. The arrangement described by Podbielnak includes a control device which is adapted to maintain a constant pressure in the column. A manometer which is connected with the vapor outlet tube by a side arm is provided with electrodes leading to an electrical circuit which includes a solenoid valve. The valve controls the effective pressure applied from a source of constant air pressure to a body of liquid air in a flask. In the operation of the Podbielnak arrangement, pressure increase in the fractionating column is registered on the mercury column of the manometer, closing the circuit through the solenoid valve and applying pressure to the liquid air which is forced into the cooling section of the column, thereby reducing the fractionation pressure. My invention is a manifest improvement over the arrangement of the patent in providing fully automatic control of the fractionating pressure in an advantageous and expedient manner and with the elimination of electrical circuits, solenoid valves and other relatively expensive equipment which have heretofore been considered essential to the operation of such devices.

Referring to the drawing:

Figure 1 is a general view of an analytical fractionating column and manometer incorporating my improvement.

Figure 2 is a sectional detail of the valve control shown in Figure 1.

With specific reference to Figure 1, 1 is an analytical fractionating column of the general type described in Podbielnak Patent 1,967,258,

having heating element 2 and a cooling zone 3 forming a receptacle at the top of the column provided with an outlet 4 and inlet conduit 5 connected with a supply 6 of liquid air or nitrogen, which is adapted to be forced by compressed air pressure through conduit 7 into the cooling section in an amount proportionate to pressure variation in the fractionating column in a manner hereinafter described. The overhead vapors from 10 the fractionating process pass through conduit 8 to an accumulator not shown. Conduit 8 is provided with a side arm 9 which connects with a mercury manometer 10 fixed to the meter stick 11. The arm 10A of the manometer connects with 15 conduit 7 and is provided with a floating needle valve designated generally at 12 in Figure 1 and shown in detail in Figure 2. As clearly shown in Figure 2, arm 10A is vented to the atmosphere through air vent 13 and has an elongated relatively restricted section 14 through which the head 15 of the needle valve will barely pass. The needle valve may be formed of any suitable material either solid or hollow according to the specific gravity of the manometer fluid, the main prerequisite being that it floats on the body of fluid in the column. In the present application I prefer to construct the needle valve of solid glass with an enlarged lower portion for contact with the manometer fluid. A constriction 16 is provided in the arm 10A to limit the downward movement of the needle valve.

The arm 10A is provided with a side arm 17 connected with a source of air under constant pressure. It will be understood that the inside diameter of the restricted portion 14 of the arm 10A is slightly greater than the outside diameter of the needle valve head 15, so as to allow a continuous small flow of air through the vent, the magnitude of which is dependent on the position 20 of the needle valve 12. A leveling bottle 18 having a pinch clamp 19 is connected with the manometer tube 10 at the bend thereof.

In operation, heat is applied to the bottom of 25 the fractionating column and overhead vapors pass through the line 8 to the accumulator, not shown. The pressure variation in the fractionating column is registered on the manometer column fluid which cause the needle valve to rise and fall relative to the restricted portion 14. 30 The quantity of air under constant pressure from air line 17 passing head 15 to the bent 13, and likewise the pressure imposed on the liquid air supply 6, is therefore, a function of the pressure in the fractionating column. It is therefore obvious that increase of pressure in the fractionat-

ing column will force an increased quantity of liquid air into the cooling zone 3 reducing the pressure in the column. During normal operation and while the pressure in the column is constant a small quantity of liquid air is continuously forced into the cooling zone. By regulation of the compressed air pressure admitted at 17 and by adjusting the mercury level with the leveling bottle 18 it is possible to fractionate under any desired constant pressure automatically and without attention of the operator.

The foregoing explanation and accompanying drawings merely illustrate one embodiment, and various changes may be made within the scope of the appended claims without departing from the spirit of the present invention.

I claim:

1. In a fractional distilling apparatus the combination comprising a source of fluid under constant pressure, a first conduit connecting said source and a supply of cooling liquid, a distilling column, a heat exchanger for cooling the upper portion of the column, a second conduit conducting cooling liquid from the supply to the heat exchanger in response to said pressure, a bleed valve in said first conduit for varying the pressure therein, and means responsive to the pressure in

said distilling column for varying the opening of said bleed valve whereby the amount of cooling liquid entering said heat exchanger is varied so as to keep said pressure in said distilling column substantially constant.

2. In a fractional distilling apparatus the combination comprising a source of fluid under constant pressure, a first conduit connecting said source and a supply of cooling liquid, a distilling column, a heat exchanger for cooling the upper portion of the column, a second conduit conducting cooling liquid from the supply to the heat exchanger in response to said pressure, a bleed valve in said first conduit for varying the pressure therein, a U tube communicating at one end with the distilling column and at the other end with said first conduit, a heavy liquid in the lower part of the U tube responsive to the pressures in the first conduit and the distilling column through the respective ends of the U tube, said bleed valve including a valve head floating in said heavy liquid, whereby the amount of cooling liquid entering said heat exchanger is varied so as to keep said pressure in said distilling column substantially constant.

DONALD R. DOUSLIN.
